UNITED STATES PATENT OFFICE.

NATHANIEL MARSHALL, OF ARKWRIGHT STREET, NOTTINGHAM, COUNTY OF NOTTINGHAM, ENGLAND, ASSIGNOR TO W. S. THOMSON & CO., OF LONDON, ENGLAND.

KNITTING-MACHINE.

SPECIFICATION forming part of Letters Patent No. 288,648, dated November 20, 1883.
Application filed May 20, 1881. (No model.) Patented in England October 22, 1880, No. 4,315.

To all whom it may concern:

Be it known that I, NATHANIEL MARSHALL, of Arkwright Street, Nottingham, in the county of Nottingham, England, have invented certain Improvements in Knitting Machines, of which the following is a specification.

The object of this invention is to produce spots, checks, and diaper patterns in one or more colors in hosiery and other goods by circular-knitting machines. Attempts have already been made to regulate automatically the supply of colored threads to such machines for the purpose of producing circular stripes; and it is by a modification of the mechanism used for this purpose that I am enabled to break up into parts the circular stripes and produce instead thereof detached patterns. This I effect, mainly, by the introduction of a compound wheel which will "impress" selected needles or press all the needles, as desired. To an ordinary circular head fitted with bearded needles I apply two or more thread-layers, which are capable of being rocked into and out of position by means of an endless chain of tappets acting on their rear ends. A tendency is given to these thread-carriers by means of springs to rise out of action, and in either of their extreme positions they are locked by means of a spring-hinged catch-bar. For the purpose of depressing the thread-carriers, so as to present the required thread to the needles, the endless chain of tappets is employed. This chain is driven by gearing from the central shaft of the machine, and it thus receives a traverse motion timed relatively to the rotation of the circular head. As a thread is presented to the ring of needles, it will be laid by the rotation of the ring of needles around the head, the thread being guided to its proper level by a fixed guide, and then carried round under the action of a series of wheels, which completes the knitting of the fabric. The thread will come first under the action of the looper-wheel, which will press in the thread, so as to indent it or provide the requisite amount of slack. The thread thus indented will pass under the action of the divider-wheel, which divides the threads more carefully into loops and raises them under

the beards of the needles. The thread in this raised position is now carried past the compound presser-wheel, which consists of disks that act upon selected needles only or upon all the needles, as the case may be, depressing their beards, so as to allow of the formed loops on the needle-stems being forced onto the beards of the needles, ready to interlock with the imprisoned threads, and form therewith a fresh course of work. As the thread passes from the presser, it will come under the action of an additional divider-wheel, for the purpose to be presently explained. After this, a knocking-over wheel will come into action, to push the formed loops over the needles to the back thereof. While that portion of the presser-disk is in action which presses only selected needles, two, three, or even four laps of thread may be laid around the circular head. It will then be necessary to press all the needles, not only to prevent too large an accumulation of thread under the beards of the impressed needles, but to prevent too great a distortion of the knitted work. When bringing into action the plain disk, or that part of the presser which acts upon all the needles, a shifting of the thread-layers will at the same time take place. This shifting will be effected, as before stated, by the chain of tappets, which in the act of forcing down a fresh thread-layer into place will tip the hinged spring-catch, and thereby release the thread-layer last in use, and allow it to rise out of action. This done, the catch will return to its locking position. The act of depressing a thread-layer to bring it into use will cause the arm of a scissor-blade to rock, and thereby close that blade upon a fixed blade, over the edge of which the thread last laid in the machine is drawn. This closing of the scissors will sever the thread, and its loose end will be caught in a brush provided for that purpose. This action of the scissors will be repeated after every change of thread. A loose-end will thus be presented by the work, and it is for the purpose of drawing such end within the knitted fabric that the dividing-wheel, situate between the presser-wheel and the knocking-over wheel, is provided. The compound presser in its simplest

form will consist of an indented or toothed disk cut to suit the desired pattern, and mounted loosely on a vertical spindle, which is free to turn in a socket-bearing of an adjustable bracket-arm. Attached to this spindle is a plain, or it may be a toothed, disk, which, when in action, will overlie the gaps in the pattern-disk and press all the needles presented to it. The spindle of this wheel bears upon a rock-lever, which is raised by means of tappets on the chain, before mentioned, for the purpose of keeping the plain disk out of action. When the rock-lever is released from this pressure, it will by the action of a spring be drawn down to a level, to act upon the beards of the needles.

In the accompanying drawings, Figure 1 is a plan view, and Fig. 2 an elevation, of a circular-knitting machine arranged according to my invention, five thread-layers being employed for throwing into the work at pleasure any one of the five different threads.

In these figures, A is the main framing, furnished with a central pin, upon which the circular head is mounted.

B is a cylinder, of cast-iron, mounted on the central pin, and free to rotate thereon. This cylinder carries a ring of vertical bearded needles, *b*, which are cast in leads, as usual, and are made fast to their cylinder by segment clamping-plates *B'*. Attached to the under side of the cylinder, or cast therewith, is a concentric bevel-wheel, *B*², which gears into a bevel-pinion, *B'*, on a horizontal driving-shaft, *B'*, which shaft has its bearings in the main framing A, and it is by the rotation of this shaft that the ring of needles *b* is caused to turn around the central bearing-pin.

*B*³ is a spur-wheel attached to the underside of the cylinder B, and serving to communicate motion through suitable gearing to an endless tappet-chain, C. This chain is laid over a chain-wheel, C', which is mounted loosely on a stud-axle carried by a bracket-casting, C², which is bolted to the main frame A.

Cast with the chain-wheel C' is a worm-wheel, C³, into which gears a worm, C⁴, keyed to a horizontal shaft, C⁵, which has its bearings in the main frame A. Fitted to this shaft by means of a feather is a bevel-pinion, C⁶, which gears into a bevel-pinion, B⁶, cast with a spur-pinion, B⁷, which gears into the spur-wheel B⁵, before mentioned. These spur and bevel pinions B⁶, B⁷ are carried by a stud-pin 55 pendent from a segment-shaped frame, A', which partially surrounds the cylinder B, and is firmly secured by bolts to the main frame A.

A' is a plate made fast to the central pin before mentioned, and serving to carry certain parts of the mechanism, to be presently described.

D D' D² D³ D⁴ are thread-carriers mounted loosely on a stud-axle, D⁸, carried by the bracket C². These thread-carriers are formed with a pendent incline, d, at their outer or rear ends to receive the pressure of tappets *c*, car-

ried by the chain C. At the rear extremity of these thread-guides (see detached view, Fig. 3) is a V-shaped projection, *d*, for a spring catch-bar, D⁵, to bear against, and thus retain any one or more of the thread-carriers in a raised or a depressed position. When this catch-bar bears on the upper side of the V projection *d*, as shown by the dotted lines, the thread-guide to which that projection belongs will be in its normal or raised position, it being drawn up after depression by the tension of a coiled spring, D⁶, which connects it with a fixed bar, D⁷, that constitutes a guide for the several threads of the thread-carriers. This guide-bar is bolted to a bracket-arm, C⁷, attached to the bracket-casting C². The depression of the thread-guides, to bring them into the drawn position of Fig. 3 for laying a thread under the beards of the needles *b*, is effected by the pressure of special tappets *c* upon the inclined projections *d*. As the rear end of any one of the thread-guides is forced upward by this pressure, the spring catch-bar D⁵ will yield and allow the projection *d* to pass 90 it. The catch-bar will then take up the drawn position of Fig. 3 under the projection *d*, and thereby retain the thread-guide at a level below the beards of the ring of needles. So soon, however, as a fresh tappet comes up to 95 act upon another thread-guide, the projection *d* of that thread-guide will trip up the catch-bar D⁵, thereby releasing the thread-guides which it had locked in a depressed position, and leaving it free to rise out of work. When 100 a thread-guide is required to be thrown out of action, another thread-guide will have to take its place. As this movement is effected, the first thread-guide will be disengaged from the catch-bar, and its coiled spring D⁶ will be free 105 to come into action and raise the thread-guide up to the dotted or inactive position of Fig. 3. The thread may be drawn from spools situated in any convenient position and led through the thread-guide bar D⁷ to the eyes of the several thread-carriers, and thence to a fixed brush, D⁸, adjustably mounted on a bracket, C⁸, bolted to the bracket-arm C⁷. As the threads of which the knitted work is to be 110 formed are lifted out of use, they will severally 115 be drawn across the fixed blade of a pair of scissors, E. This blade lies horizontally, and is made fast by a cranked stem to the bracket C⁷. Pivoted also to the same bracket is the movable blade of the scissors, its cranked stem being furnished with a pin, e, that projects into the slot at one end of a double-cranked rock-lever, E', which is pivoted on the same bracket, C⁷. This lever E' carries a bowl, e', which stands in front of an incline, 120 d', projecting from the under edge of the several thread-carriers. When, therefore, any one of the thread-carriers—say D'—is depressed to bring its thread into use, the previously-depressed thread-carrier—say D—will 125 require to have its thread severed to disengage it from the work. This, it will be seen,

is effected by the pressure of the incline d^2 of the depressed thread-carrier D' coming into contact with the bowl c' , and thereby rocking the crank-lever E' , which, through the pin e , will close the moving blade of the scissors onto the fixed blade, and thereby sever the thread which the ascending thread-guide had so placed as to be ready (by the continued traverse of the needles) to be drawn into the required position for being severed. Before, however, this action has taken place, the thread will have been caught by the brush D'' , and its end will thus be secured ready for renewing the knitting operation with that thread.

15 The thread-guides are made of thin steel, and to secure compactness and to prevent all tendency to torsion a comb-guide, D'' , is provided for them to work in. This will also steady their movements, which, as before explained, 20 are independent the one of the other, thus necessitating the mounting of the thread-guides loosely on their common fulcrum pin or support.

To insure the threads being brought into line with the looper-wheel, a fixed guide, F , is provided, which, being slightly inclined upward, leads the thread, as it is drawn forward by the rotation of the ring of needles, immediately under the action of the looper-wheel. 25 The looper-wheel G is constructed and mounted in the ordinary manner, the bracket G' , which carries it, being adjustable vertically on the segment-shaped frame A' . The socket, which carries the adjustable spindle of the 30 wheel serves also to support the thread-guide bar F . The thread, after being pressed by the looper-wheel upon the stems of the needles b , in a manner to provide the requisite slack for the knitting, next passes under the action of 35 the divider-wheel G^2 , which divides up or equalizes the slack and pushes the thread under the beards of the needles. This divider-wheel is mounted in a similar manner to the looper-wheel, and upon the same segment-frame, A' . The needles are now ready to be 40 pressed, and their continued travel brings them under the action of the presser-disk H , which is cut to suit the pattern intended to be produced. This disk is supported upon a bracket-arm, H' , carried by an adjustable bracket, H^2 , on the segment-frame A' . Through the hub of the presser-disk H , (see Fig. 4,) and through a socket in the bracket-arm H' , passes a vertical spindle, H^3 , which serves as an axle 45 for the presser-disk H to rotate on, and carries also a presser-disk, H^4 , which, when in position for knitting, will lie close to the disk H , and will press the beards of all the needles 50 as they are brought round, thereby neutralizing the effect of the "mispressing" wheel H . The spindle of this disk H rests upon a lever, H^5 , which has its fulcrum at H^6 , and when the tail of this lever is depressed, the disk H^4 will be raised, when the pattern presser-disk H 55 will be free to act upon selected needles, and thereby produce the required pattern in the

work. The tail of the lever H^5 is acted upon by the rocking lever H^7 , which is mounted on the fulcrum D^8 , that carries the thread-guides, and is so shaped at its rear as to receive the pressure of tappets h , carried by the traveling chain C . These tappets are so arranged as to cause the levers H^5 and H^7 to lift the presser-disk H^4 , and hold it out of action while the pattern is being worked, and then to release 75 the presser-disk H^4 , and leave it free to drop upon and cover the patterned disk-presser, in order that the plain knitting may be resumed. When it is desired to alter the pattern, it will only be necessary to lift out the compound presser, to change the presser-disk H for another of the required pattern, and then to replace the disks in the machine. On the beards of the needles being closed, as above explained, the loops of the last row 80 knitted on the needles are lifted in succession up onto the beards by means of the "handing" wheel I , which wheel is mounted on the central plate, A^2 , and, like the other disks, the looper, divider, and presser-wheel, gears with 85 the stems of the needles. The further progress of the ring of needles brings the thread which is under the beards of the needles opposite a second or additional-divider-wheel, G^3 , which 90 equalizes the size of the loops and causes the 95 loose-ends to be taken up into the work, which loose ends are due to the shifting of the threads into and out of use and the cutting off of those threads which have been thrown out of use. This divider-wheel is mounted loosely on a 100 vertical pin which is fast on a bracket bolted to the frame A' . The knitting now proceeds as in the ordinary circular-head machines—that is to say, the work is brought under the action of a knocking-over wheel, K , situated within the ring of needles, and supported on the central plate, A^2 . By this wheel 105 the formed loops are forced off the needles, the action being assisted by an upward drag put upon the work. The further rotation of 110 the ring of needles brings the newly-formed loops under a fixed guide, L , within the ring of needles, which guide, assisted by a wheel, K' , external of the ring of needles, will depress 115 the loops to a position on the needle-stems 115 suitable for the commencement of a new row of loops.

As the working of this class of knitting machinery is well understood, it will not be necessary to follow more closely the motions of 120 the several instruments employed in producing the work; but I have thought it desirable by the aid of diagrams to illustrate the mode in which the spots are produced.

The diagram Fig. 5 shows the face or front, 125 and Fig. 5^a the back, of a piece of work equal in width to eight needles and of a depth of seven loops. This work is supposed to consist of a plain and a colored thread, the plain thread forming the ground and the colored 130 thread the spot or pattern. The knitting, it will be understood, proceeds, as usual, with

the plain thread until, by the depression of a fresh thread-carrier, a colored thread is introduced. The presser-disk H' being at this time lifted, the patterned presser-disk will be free to act. Consequently as the needles are brought round past the presser-disk, those needles only will be pressed which are designed to produce the spot, and the other needles being missed, the colored thread will be brought under their beards and left to form a floating thread in the work. In the diagram the spot is represented by two loops in breadth and three in depth. Consequently the ring of needles will have to make three rotations before a spot is completed. This having taken place, the presser-disk H' will be allowed to drop into the acting position, ready to press upon the beards of all the needles at the next rotation of the ring, and thereby produce an unbroken line of loops. Before, however, this is effected, the thread-carrier, with its colored thread, must be lifted out of action and replaced by the plain-thread carrier in the manner already explained, at which time the scissor-blade will be caused to sever the colored thread and leave a loose end in the work. It is to insure the knotting of this "loose end" into the work, whether it be a colored or a plain thread, that the additional divider-wheel G¹ is provided.

It may be found desirable to provide two or more patterned disks, which will be brought into action as required to introduce varieties of patterns by varying the "tucking" of the work. In such case the plain presser-disk is situated between the two patterned disks, and it is thrown into or out of action, as desired. This modification is illustrated at Figs. 6, 7, and 8, where Fig. 6 is an elevation of the compound presser detached from the machine. Fig. 7 is an elevation of the parts of the machine used in actuating the presser, and Fig. 8 is a plan view of the same, the presser in the latter view being shown in place. In this example, H and H* are the patterned presser-disks, and H' is the plain presser-disk, which is capable of being thrust between the two patterned disks and withdrawn automatically by means of the tappet-chain C. These cut presser-disks H, H* have stud-axes or pins, which are each carried or mounted in a journal formed to receive them in the ends of the upper and lower prongs of a forked extension of the ordinary adjustable bracket-arm, H'. The pin H³ of the upper presser-disk, H*, passes through the bearing in the upper prong of the arm H', and is embraced by the prongs of the forked rocking lever H⁵, which serves to lift it out of work. The fulcrum of this rock-lever is carried by a bracket that is bolted to the segment-frame A'. The rocking of this lever H⁵ is effected through a lever, H⁶, and tappet-chain C, as before explained. The disk H' is mounted loosely on a pin carried by a horizontal cranked lever, H⁷, having its fulcrum on a vertical pin, H⁸, carried by the bracket H⁹ from the segment-frame A'. The tail of the

cranked lever H⁷ is brought under the action of a rock-lever, H¹⁰, mounted by the side of the rock-lever H⁵, and, like it, brought into action by suitable tappets on the tappet-chain C. H¹⁰ is a coiled spring, which will cause the presser-disk H' to be held against the beards of the needles with sufficient pressure to close them, which pressure can be regulated by the set-screw H¹¹. When, therefore, plain knitting is required, the disk H' will be held in its working position; but when pattern-work is required, it will be drawn back out of action, a tappet on the tappet-chain raising the underlying rear end of the lever H⁵, and one or both of the disks H and H* will press the beards of the advancing needles. The cut of these two disks will be such relatively to each other that the lower, H, will produce a given pattern. The upper disk, when brought to act with the lower one, will act so as not to be interfered with by the lower disk, or only in some determined degree. So soon as the pattern is completed, the upper disk, H*, will be raised out of action, and the lower disk, H, will either be allowed to act alone or the disk H' will be advanced, so as to press all the needles and produce the ordinary plain work.

By mounting the compound presser-wheel so that the disks composing it shall be raised out of and lowered into working contact with the needles, the acting surfaces of said disks always preserve their adjusted relation to the beards of the needles, and, moving in a vertical plane parallel with that occupied by the needles, no injurious bending of the needles can take place, as is liable to be the case where the movement of the disks is at right angles to the needles, and their throw may accidentally be so great as to effect such injury to the needles or their beards.

Having now set forth the nature of my invention of improvements in knitting machinery and explained the manner of carrying the same into effect, I wish it to be understood that I claim—

1. The combination, with the needle-cylinder, needles, and automatically-changing thread-guides, of a compound presser constructed and automatically operated so as to press the beards of all the needles or to miss a portion of them, and a tappet-chain operating to produce a conjoint action of the said guides and presser in knitting spots, checks, or diaper patterns, substantially as described.

2. The combination, with the bearded needles of a knitting-machine, of a rotary presser consisting of a patterned disk revolving upon a fixed axis, and a plain disk mounted upon a movable axis, and means for reciprocating said plain disk in a direction parallel with the needles, whereby said plain disk may be brought into and thrown out of operative position, substantially as described.

3. The combination, with the bearded needles of a knitting-machine, of a rotary presser

consisting of a patterned disk revolving upon a fixed axis, a plain disk mounted upon a movable axis, a second patterned disk rotating on a movable axis, and means for carrying said plain disk and last-mentioned patterned disk into and out of operative position, substantially as described.

4. The combination, with the needle-cylinder, needles, changeable thread-guides, and to an appliance for severing the threads, of the divider-wheel G, for equalizing the size of the

loops and working the loose ends of the severed threads into the fabric, substantially as described.

London, February 16, 1881.
